UNITED STATES PATENT OFFICE

139,288

DESIGN FOR A BANNER

Leif George Johnsen, New Rochelle, N. Y.

Application June 13, 1944, Serial No. 113,977

Term of patent 3½ years

(Cl. D29—17)

To all whom it may concern:

Be it known that I, Leif George Johnsen, a citizen of the United States and resident of New Rochelle, in the county of Westchester and State of New York, have invented a new, original, and ornamental Design for a Banner, of which the following is a specification, reference being had to the accompanying drawing, forming a part thereof.

The figure is a front view of a banner, showing my new design.

I claim:

The ornamental design for a banner, substantially as shown.

LEIF GEORGE JOHNSEN.
